UNITED STATES PATENT OFFICE.

WILLIAM P. GRANT, OF SALINAS, CALIFORNIA.

SAFETY-POCKET.

1,256,787.

Specification of Letters Patent. Patented Feb. 19, 1918.

Application filed July 13, 1916. Serial No. 109,123.

To all whom it may concern:

Be it known that I, WILLIAM P. GRANT, a citizen of the United States, residing at Salinas, in the county of Monterey and 5 State of California, have invented certain new and useful Improvements in Safety-Pockets, of which the following is a specification.

My invention relates to wearing apparel, 10 and more particularly, to an improved safety pocket.

The invention has more especial reference to a pocket of the character stated, which will positively prevent the loss of various articles therefrom, irrespective of the position 15 of the same, and also one which will prevent the theft of matter therefrom.

More particularly, the present invention has reference to the novel construction and 20 arrangement of the safety attachment for the pocket, the same comprising several pieces of material affixed to the pocket, adjacent the mouth thereof, and having their side marginal edges partially united by stitching; a resilient frame being attached to each 25 of the pieces and extending about the side and lower marginal edges thereof, thus, causing the same to be yieldably held together.

30 All of the foregoing together with additional advantageous details and arrangement of the parts of the preferred embodiment of my invention, will be clear from the specific description hereinafter contained, 35 when read in connection with the accompanying drawings forming a part hereof, wherein said embodiment of the invention is illustrated for the purpose of facilitating a full understanding of the present invention.

40 In the drawings:—

Figure 1 is a front elevation of the pocket with my improved safety attachment applied thereto, showing a portion of the pocket broken away to indicate the arrangement of the safety attachment therein,

45 Fig. 2 is a longitudinal section taken on the line 2—2 of Fig. 1, and

Fig. 3 is a perspective of the improved 50 safety attachment.

Referring now more particularly to the drawings, and in connection with which like reference numerals will refer to the same parts throughout the several views, I 55 have indicated the wearing apparel generally by the numeral 1, while the pocket is

designated by the numeral 2. The present invention comprises several strips of flexible material, such for instance, as that from which the garment is made, these pieces being indicated by the numerals 3 and 4. The upper marginal edges of the flexible pieces 3 and 4 are hemmed, as shown at 5 and 6 and then attached to the pocket at a point, adjacent the mouth thereof by means of the 60 usual stitching. The flexible pieces 3 and 4 are tapered slightly and have their side marginal edges united by stitching as at 7 and 7' for a portion of the length thereof, thereby allowing the pieces to be moved 70 apart at their lower portions. The remainder of the side portions is left open, thus providing for means whereby the same may be separated sufficiently to admit the hand of the wearer. It will also be noted 75 that the top portion of the flexible pieces 3 and 4 are so united as to permit that portion of the same to bow, thus, enabling the user to readily insert his hand in the pocket when desired. To provide for means whereby the lower portion of the flexible pieces 3 and 4 and the open side portions thereof 80 may be normally held together, I affix to each of the said pieces, adjacent the lower and side marginal edges thereof, a frame 85 comprising a single strip of wire bent upon itself to constitute a pair of resilient jaws 8 and 9. These resilient jaws 8 and 9 are preferably secured to the lower and side marginal edges of the flexible pieces 3 and 90 4 by turning portions thereof over and securing the same by stitching, thus providing for efficient pocketing means.

From the foregoing, it will be evident, 95 that the hand of the user may be readily inserted within the pocket, inasmuch, as the said flexible pieces 3 and 4 are so connected as to permit the same to readily move apart when desired. Thus, when an article is placed within the pocket 2, the same will be 100 prevented from passing or becoming displaced therefrom, by means of the safety attachment as formed by the flexible pieces 3 and 4, it being noted, that the lower and side marginal edges of the same are normally held together by means of the resilient jaws 8 and 9 which are affixed thereto adjacent said edges. Should the pocket be inverted the articles as contained thereby, will then become lodged between either 105 of the flexible pieces 3 and 4 and the side walls of the pocket 2, the said resilient jaws 8

and 9 possessing sufficient resiliency to hold the same together and prevent the articles from wedging themselves therebetween.

It is to be appreciated, that the device 5 may be applied to any form of pocket and is especially adapted for use by mechanics and other persons whose work compels them to bend into various positions, consequently, inverting their pockets, and causing the 10 various articles as contained thereby to move toward the mouth thereof, and consequently lost. It will be also appreciated, that the device will provide efficient means for preventing the pocket from being picked by 15 thieves, the wires possessing such resiliency as will cause the pocket to sag slightly when the hand is passed therebetween, consequently imparting a pull to the garment of the person.

20 While I have herein disclosed a specific embodiment of the invention, it will be apparent to persons skilled in the art, that the invention is capable of embodiment in other forms and devices, differing in detail and 25 arrangement from that shown, as may be in keeping with the hereto appended claim.

Having thus described the invention, what is claimed is:—

30 In a pocket, the combination of a safety device therefor, comprising a pair of flexible pieces, the upper edges of said pieces being looped over and stitched to said pocket ad-

jacent the mouth thereof, said pieces being of substantially the same length as the entrance to the pocket adjacent their upper 35 edges, said pieces having their side edges converging toward the lower edges thereof, said pieces being stitched along their side edges from points adjacent their upper edges of said pieces to points adjacent the 40 center thereof, whereby the lower portions of said pieces and portions adjacent the side tapered edges will be free to open, a wire frame formed of a single strand of wire and being bent to form resilient jaws, the side 45 portions of said jaws diverging toward their upper portions, the free side edges of said pieces being looped around said jaws and stitched upon themselves for providing an even inner surface between said jaws, said 50 jaws being of substantially the same size so as to be in direct alinement with each other when in a normal condition, thus forming a tight closure for the free portion of said pieces although allowing the wearer to insert a hand for urging the jaws apart and permitting access within said safety device 55 when desired.

In testimony whereof I affix my signature in presence of two witnesses.

WILLIAM P. GRANT.
